UNITED STATES PATENT OFFICE.

OSCAR J. LEINS, OF MILWAUKEE, WISCONSIN, ASSIGNOR TO MILWAUKEE GAS SPECIALTIES CO., OF MILWAUKEE, WISCONSIN, A CORPORATION OF WISCONSIN.

FLASH IGNITER.

Application filed January 21, 1924. Serial No. 687,507.

My invention relates to flash igniters for gas burners and the like, and more particularly to flash igniters of the reciprocable as distinguished from the rotary valve type.

5 The invention is illustrated in the accompanying drawings, in which:

Figure 1 is a side elevational view of an igniter embodying the invention;

10 Fig. 2 is an enlarged longitudinal section through the valve and firing tip of Fig. 1;

Fig. 3 is a transverse section through the plunger housing on line 3—3 of Fig. 2.

Fig. 4 is a fragmentary side elevational view of a modified form of firing tip; and

15 Fig. 5 is a top plan view of the tip shown in Fig. 4.

In the drawings the valve cage or casing 5 is mounted directly on and opens directly into the fuel supply pipe 6 which may be 20 the main gas supply pipe of the stove, for example.

Cage or casing 5 constitutes the plunger housing. It is formed of standard hexagon stock, preferably brass, and comprises an intermediate hexagonal faced body portion 25 7 having an upwardly extending tubular projection 8 and a depending nipple 9 threaded at 10 into supply pipe 6. Tubular projection 8 and nipple 9 are coaxial and 30 both are eccentrically disposed with respect to the intermediate body portion 7 to leave sufficient stock to one side of the common axis of projection 8 and nipple 9 for a union fitting for the torch tube 12 which leads to 35 the firing tip or head 13.

The lower end of cage or housing 5 projects into the interior of pipe 6 and forms a seat engageable by the head 14 of a plunger valve 15 whose stem 16 extends upwardly 40 through chamber 17, slidably through a guiding and packing seating flange 18 and up through a chamber 19. Chamber 17 is bored up axially through nipple 9 and up into body portion 7 to the annular plunger 45 guiding and packing seating flange 18 and chamber 19 is bored down through tubular projection 8 to flange 18 and coaxial with chamber 17. The diameter of bore 17 is larger than the diameter of stem 16 and 50 forms an annular passage or chamber about the stem. A duct 20 opens from chamber 17 into tube 12, said tube having its valve end flared out at 21 and secured in a transverse threaded bore 22 in the off center body 55 portion 23 by a union nut 24 threaded into

bore 23 and provided with a hexagonal head 25.

A passage or duct 26 axially through the head 14 and stem 16 opens into annular chamber 17 through a transverse duct 27 60 and with duct 27 constitutes a by-pass through which a restricted flow of fuel is permitted to igniting tip 13 to maintain the small pilot light which normally issues therefrom. The restricted or by-pass supply 65 from duct 26 through duct 27 and thereby the pilot light at the jet is decreased or increased by a valve pin 28, having a lower needle end for metering the fuel flow from duct 26 to tube 12 and having threaded engagement at 49 with the interior of the upper end of stem 16. At 50 the threaded portion of pin 28 extends loosely through a button 51 and has at its upper end a head 52 which fits in a recess 53 in the head of button 70 51, head 52 having a screw driver slot 54 for threading it into and out of stem 16 and the lower end of duct 26 terminating in a screw driver slot 55 for threading the plunger into button 51. 75

The shank of button 51 threads at 59 upon the upper end of stem 16 and is slidably mounted in bore 19. The upper surface of annular flange 18 is inclined outwardly and seated upon said surface is suitable packing means 56 in the form of a fabric or fibre washer and a metallic ring or washer 57 is arranged about stem 16 upon packing 56. Button 51 is normally projected upwardly and head 14 into closed engagement with the inner end of nipple 9 by a coiled spring 58 interposed between washer 57 and the inner or lower end of the shank of button 51 and fitting at its outer end into a recess in said button. 90 95

The tip 13 shown in Figs. 1 and 2 is enlarged at its inner end and threaded at 60 upon the outer end of tube 12, and is tapered outwardly and provided with outlet ports 61 which preferably correspond in number to the number of burners, etc. grouped about the igniter and so aligned that an igniting flame will be projected upon each burner of the group when the valve is operated. 100 The jet may be a single or multiple one and 105 may be with or without a protecting hood, as desired.

In Figures 4 and 5 the outer end of tube 12 is turned up at 62 with the tip 13' disposed vertically instead of horizontally and 110

provided as before with outlet ports 61' through which the flame is directed toward the desired burner or burners.

In operation a small pilot light is normally maintained at the jet by the passage of fuel from pipe 6 through ducts 26 and 27, chamber 17, duct 20 and tube 12 to the jet. The size of the normal pilot flame may be adjusted as desired by screwing pin 28 into 10 or from stem 16. To ignite one or a plurality of burners, button 51 is depressed to unseat valve head 14 whereupon the fuel supplied to the jet is directly through the open end of plunger housing 5. This increases the supply to the jet and projects a long slender flame to the burner or to a number of burners for lighting same.

It should be noted that the interior of the supply pipe itself provides the necessary 20 clearance for the reciprocable movement of plunger head 14. There is no valve body between the plunger housing and the supply pipe and the number of joints which must be kept tight and the number of parts are 25 thereby minimized. The nipple 9 and projection 8 which are coaxial with respect to each other and formed eccentric with respect to body portion 7 as for example on an automatic screw machine, or otherwise, lends 30 itself admirably to this arrangement and provides for connection of tube 12 to one side of the body 7 of the plunger housing, the off center arrangement of nipple 9 and projection 8 providing sufficient stock at one 35 side of the intermediate portion of the plunger cage or housing for the lateral connection to tube 12.

I claim:

1. In a device of the class described, the combination of a supply pipe, a firing head, a valve cage having a nipple threaded directly into said pipe, the inner end of said nipple forming a valve seat within the supply pipe and valve means mounted directly in said cage, cooperable with said seat and reciprocable within the supply pipe for controlling the fuel supply to the firing head.
2. In a device of the class described, a valve cage formed of non-circular stock with an eccentric nipple projecting from one end and threaded to be screwed directly into a tapped opening in a supply pipe, and a tubular projection coaxial with respect to said nipple projecting from the opposite end of said cage, a torch tube opening laterally into the valve cage through the off center intermediate portion thereof and a valve mounted directly in the valve cage, said valve being reciprocable within the supply pipe and cooperable with a seat on said cage for controlling the fuel supply to said torch tube.
3. In a device of the class described, the combination of a supply pipe, a valve cage

having a non-circular intermediate body portion, a nipple projecting eccentrically from one end of said cage and threaded to be screwed directly into said supply pipe, a tubular projection extending from the opposite end of said body portion coaxial with respect to said nipple and eccentric with respect to said body portion, the nipple forming a valve seat within the supply pipe and being bored axially up into the intermediate body portion, the tubular projection having a coaxial bore, an intermediate guiding and 70 packing seating flange between said bores, a torch tube opening laterally into said first bore, a reciprocable plunger mounted directly in said valve cage, said plunger extending axially through said bores and said 75 intermediate flange and having a head at its lower end reciprocable in the supply pipe and cooperable with the inner end of the threaded nipple, packing on said annular flange and about the plunger, a push button 80 on the upper end of the plunger, said button having a shank reciprocable within said second bore, a spring interposed between the annular flange and said button, by-pass means opening from the supply pipe to the 85 torch tube when the plunger head is in engagement with the nipple, and a metering pin threaded into said plunger for adjusting the normal by-pass flow of fuel, said pin having a head fitting in a recess in the push 90 button.

4. In combination, a supply pipe comprising a relatively thin walled tube, a valve cage threaded directly into said tube and forming a valve seat within the tube, a 100 plunger valve mounted directly in the valve cage and having a head cooperable with said seat and reciprocable in the tube, said cage having a bore surrounding said valve, packing means in the cage along the plunger for 105 sealing said bore and a torch tube attached directly to said cage and opening into said bore between the supply pipe and said packing means.

5. In a device of the class described, a valve cage having an intermediate off center portion, a reciprocable controlling valve mounted directly in said cage, coaxial projections extending from opposite ends of said intermediate portions eccentrically 115 thereto, one of said projections being adapted for direct connection with a fuel supply pipe, a push button mounted on the valve member and reciprocable in the other projection and a torch tube mounted in the off center portion of the cage and opening thereinto.

In witness whereof, I hereunto subscribe my name this 17 day of January, 1924.

OSCAR J. LEINS.
